W. F. MITCHELL.

GREASE CELLAR.

APPLICATION FILED JUNE 26, 1920.

1,423,502.

Patented July 18, 1922.

UNITED STATES PATENT OFFICE.

WILLIAM FRANCIS MITCHELL, OF CLIFTON, NEW JERSEY, ASSIGNOR OF ONE-HALF TO
FRANK R. ALLEN, OF PASSAIC, NEW JERSEY.

GREASE CELLAR.

1,423,502.

Specification of Letters Patent. Patented July 18, 1922.

Application filed June 26, 1920. Serial No. 391,950.

To all whom it may concern:

Be it known that I, WILLIAM FRANCIS MITCHELL, a citizen of the United States, and resident of Clifton, in the county of Passaic and State of New Jersey, have invented certain new and useful Grease Cellars, of which the following is a specification.

My invention relates to improvements in grease cellars and the object of my invention is to provide a simple and convenient grease cellar for the purpose of lubricating axles and the like. I accomplish this object by the device illustrated in the accompanying drawing in which:

15 Figure 1 is a sectional view of the grease cellars applied to an axle; and

Figure 2 is a front elevation of the same.

Similar characters refer to similar parts throughout the several views.

20 My improved grease cellar is adapted to be applied to the underside of an axle at the bearing or journal and is supported in any suitable manner. It includes a case 1 having a bottom and side walls and an open front in which is set a box 2 which is supported by the bottom of the case 1 and is open at the top and in which the grease is contained. Within the box 2 I provide a plate 3 supported by a suitable spring 4 and 25 adapted to force upwardly a cake or block 5 of grease or lubricant which is covered with an apertured cover 6 resting against the axle 7. The box 2 is held within the case 1 by means of a bolt 9 inserted through 30 ears 10 carried by the case 1 and a lug 11 on the box 2. The bolt 9 may be held in position by a nut 12 or in any other suitable manner.

Within the box 2 near its base, I provide 35 rods 13, 14 slidable in sockets 15, 16 and on the underside of the marginal edges of the plate 3 I provide apertured lugs 16. When it is desired to hold the plate 3 in its depressed position the rods 13, 14 are inserted 40 through the lugs 16 and when it is desired to permit the spring 4 to operate, these rods 13, 14 are withdrawn.

On the underside of the plate 3 I preferably provide a rod 17 extending through 45 the bottom of the case and the box to serve as a tell tale whereby the quantity of grease on the plate may be readily determined without opening the device by merely ob-

serving the length of said rod extending below the bottom of the case. Suitable gauge 55 marks may be used on the rod 17 when desired.

The box 2 being removed from the case 1, the plate 3 is depressed and held in its depressed position by the rods 13 and 14 engaging the lugs 16 and the grease or like lubricant in solid form, cut or molded to fit within the box 2, is placed upon the plate, and the cover 6 is positioned within the box 2 upon the said lubricant. The box 2 is then placed within the case 1 and the bolt 9 inserted through the ears 10 and the lug 11 and secured in position by the nut 12. When it is desired to make use of the lubricant, the rods 16 are withdrawn, thus releasing 70 the spring 4 which forces the lubricant up against the perforated cover 6 where it serves to lubricate the axle 7.

Having thus described my invention, what I claim is:

1. In a device of the character described, the combination of an open front case having a bottom and side walls, a closed box therein resting on the bottom of the case having an open top and adapted to contain a cake of lubricant and means for securing the box in the case, substantially as shown and described.

2. In a device of the character described, the combination of a case having a bottom and an open front, a box therein, and resting on the bottom of the case, ears on the case, a lug on the box and a bolt inserted through said ears and said lug to secure the box in the case.

3. In a device of the character described the combination of a case, a box therein, a plate in the box, and adapted to support a lubricant apertured lugs on said plate, rods adapted to engage said lugs to hold 85 the plate in a depressed position, a spring below the plate and adapted to press the same upward, an ear on the case, and a lug on the box and a bolt inserted through the ear and the lug to secure the box in position.

Signed at Clifton, in the county of Passaic and State of New Jersey this 15 day of June, A. D. 1920.

WILLIAM FRANCIS MITCHELL.
